UNITED STATES PATENT OFFICE.

HENRY S. PRENTISS, OF ELIZABETH, NEW JERSEY.

ELECTRIC SIGNALING-CLOCK.

No. 879,410.

Specification of Letters Patent.

Patented Feb. 18, 1908.

Application filed August 4, 1905. Serial No. 272,715.

To all whom it may concern:

Be it known that I, HENRY S. PRENTISS, a citizen of the United States, and resident of Elizabeth, in the county of Union and State 5 of New Jersey, have invented certain new and useful Improvements in Electric Signaling-Clocks, of which the following is a specification.

My invention relates to electric signaling or 10 so-called program clocks such as are adapted to be set to close electric signaling circuits at certain periods of the day or night, and has for its particular object to simplify the means for setting the signal times and to limit the 15 duration of the signal produced when the electric circuit is closed.

My invention will be best understood in connection with the accompanying drawings in which,

20 Figure 1 is a front elevation of my electric signaling clock together with a diagrammatic sketch of the electrical connections. Fig. 2 is a side view of my device showing also the clock and driving mechanism. Fig. 3 is a 25 partial sectional view of a portion of the device. Fig. 4 is a view illustrating the action of the scissor switch. Fig. 5 is a detail view of the contact disk.

Similar numerals of reference designate 30 corresponding parts throughout the several views.

Referring now to the drawings, 1 indicates the frame of a clock-mechanism comprising the usual train of wheels. Upon the barrel 35 arbor 2 a spur wheel 3 is mounted to revolve about said arbor. This wheel 3 engages with a pinion 4 mounted to turn with the arbor 5 of the center wheel 6 and the pitch of the two wheels is such that in this particular case the 40 wheel 3 makes one complete revolution to six of the pinion 4, that is, the wheel 3 is a six-hour wheel. Carried by this spur wheel 3 and supported by means of the sleeve 7 and held in place by a collar 8 held to the arbor 2 45 by the set-screw 9, are, in this case two contact plates or disks 10 and 11 interlaid by disks of suitable insulating material 12 and 13 and covered with suitably marked disks 14 and 15 indicating the divisions of time.

50 The contact disks or plates 10 and 11, Fig. 5 are of some flexible and good conducting

material such as copper and are provided with circumferential contact teeth 16 which are normally bent upwardly about the circumference of the plates 14 and 15. When 55 required to make contact the teeth 16 are bent downwardly into the plane of the contact disks 10 and 11 against the insulating plates 12 and 13 so that they project slightly beyond the circumference of the insulating 60 plates.

The disk 13 of insulating material carries, on its under side a pin 17 adapted to wipe the lever 18 in opposition to a spring 19, the lever 18 being limited in its outward motion 65 by a pin 20.

The lever 18 is mounted to turn upon a shaft 21, as is also the ratchet wheel 22, which carries the bushing 23 provided with contact pins 24 and 25, adapted to engage the brushes 70 26 and 27. Upon the lever 18 is loosely mounted the spring-pressed pawl 28 which engages the teeth of the ratchet wheel 22 and is adapted to throw back the said wheel on the release of the lever 18 under the action of the 75 spring 19 after the lever has been advanced by the pin 17. A contact pawl 29 also engages the teeth of the said ratchet wheel 22, but this pawl is insulated from the contact brushes 26 and 27 by an insulating plate 30, 80 and the brushes 26 and 27, contact pins 24 and 25 as well as the ratchet wheel and lever are insulated from the rest of the mechanism by the insulating plate 31.

Upon the arbor 5 is further mounted a 85 ratchet wheel 32 adapted to turn with said arbor and divided into a number of teeth corresponding to the number of divisions for one hour on the contact disks 10 and 11, that is, to the number of contact teeth included 90 between the hour division upon said contact disks. This ratchet wheel is engaged by two contact pawls 33 and 34 held by suitable springs 35 and 36 and working about a common fulcrum 37 forming levers having inner 95 arms engaging the teeth of said ratchet wheel and outer arms adapted to make contact with the brushes 38 and 39. The pawls form a so-called scissor-switch which is controlled by the ratchet wheel 32 as follows—The 100 inner arm of the lever 33 is made somewhat shorter than the similar arm of the lever 34,

the difference in length determining the duration of the signal produced. As the ratchet wheel 32 revolves, the inner arm of the lever 33 is raised to the top of the tooth of the 5 wheel and thereby throws the outer arm out of contact with the brush 38. At the same time the outer arm of the lever 34 is brought into contact with the brush 39 and remains in contact until the inner arm drops into the 10 next tooth. However, as soon as the inner arm of the lever 33 drops into the next tooth, contact is made between its outer arm and the corresponding brush 38 and a circuit may be established through the two outer arms, that 15 is, from the brush 38 to the brush 39, as shown in Fig. 4, and lasting until the inner arm of lever 34 drops into the next tooth when the contact between the outer arm and the brush 39 will be broken. The duration 20 of a circuit through these brushes may therefore be made very short or comparatively long depending upon the difference in time between the dropping of the two inner arms into the next tooth, that is, by making the 25 inner arm of lever 34 of sufficiently greater length than the corresponding arm of lever 33.

The levers or pawls 33 and 34 as well as the brushes 38 and 39 are insulated from the rest 30 of the mechanism by means of the insulating plate 40.

From the brush 38 a wire 41 leads to a signaling device 42 such as an ordinary electric bell or gong and from there to the battery 35 43 finally returning through the wire 44 to a binding post 45 on the frame of the clock mechanism. The circuit 41 to 45 contains all the signaling devices such as bells, etc. and may be subdivided and arranged as desired. The signal devices are adapted to be operated at the times set on the disks 14 and 15 and the duration of the signal is limited by the scissor-switch comprising the levers 33 and 34. From the binding post 45 the circuit 40 is through the frame of the mechanism to the arbor 2 and hub of the spur wheel 3 and sleeve 7 to the conducting plates or disks 10 and 11. When the brushes 46 and 47 make contact with the flexible circumferential contact teeth 16 which are bent into the plane of disk and thus project beyond the insulating disks 12 and 13, the circuit is 45 through these brushes to the brushes 26 and 27 through the wires 48 and 49. The brushes 50 46 and 47 normally wipe the respective circumferences of the insulating disks 12 and 13 and only establish a circuit when they come in contact with an extended contact tooth 16. From these brushes 26 and 27 the circuit is 55 through the contact pin 24 engaging the brush 26 as shown or through the contact pin 25 and brush 27, thence through the bushing 23, ratchet wheel 22, to the contact pawl 29 which is connected by a wire 50 to the bind-

ing post 51 of the brush 39. From this point 65 the circuit passes through the scissor-switch comprising the levers or pawls 33 and 34 and is controlled thereby as previously explained, finally completing itself at the lead 41.

The general operation of the device is as 70 follows—The upper dial 14 as well as the lower dial 15 are in the example shown divided into six hours which are subdivided into five minutes divisions, each of which

contains two flexible contact teeth corresponding to two and one-half minutes of time. One revolution of the disk will therefore cover a period of six hours divided into two and one-half minute intervals and each 75 flexible tooth when in the plane of the disk 80 will close the circuit and give a suitable signal when it comes in contact with the brush 46. When the six hours have elapsed, the pin 17 upon the lower insulating disk 13 engages with the lever 18 carrying it inward in 85 opposition to the spring 19 finally releasing it and as the lever returns, the pawl 28 throws back the ratchet wheel 22 through the space of one tooth. This will throw the contact pin 24 out of contact with its brush 26, but 90 will at the same time bring the contact pin 25 into the contact with the lower brush 27, which is in connection with the lower brush 47 which latter brush is adapted to make contact with the flexible contact teeth of the 95 lower conducting plate 11. Thus for the next revolution of the spur wheel 3, the contact disk 11 is active for a period of six hours and the upper disk 10 is inactive during the same period. When the revolution is complete 100 the same action takes place, but in this case, as well as the next, that is, for a period of twelve hours, the contact pins 24 and 25 fail to make contact with the respective brushes 26 and 27 and the circuit therefore 105 remains open during this period, no signals being given. At the expiration of this period of twelve hours the opposite end of the contact pin 24 makes contact with its brush 26 and thereby again brings the upper disk 10 110 into action, and the same order is established. This arrangement is in accordance with the usual practice which requires the signals to be given during only a part of a day, say 6 a. m., to 6 p. m. Of course, by a 115 suitable number and arrangement of the contact pins, the periods of activity and inactivity may be made as required by the particular conditions to be met. I may also increase the number of conducting disks and 120 collecting brushes or increase the size of the disk to obtain a greater number of contact teeth and thereby shorter intervals of time. Further, I may also control a plurality of signal circuits by one and the same movement, it being necessary only to provide a sufficient number of conducting disks and 125 brushes. The circuit suspending and chang-

ing device with its contact pins 24 and 25 and its brushes 26 and 27 must of course be made more elaborate to properly take care of the increased number of circuits, but this 5 lies entirely within the skill of the ordinary electrician and presents no particular difficulty.

What I claim as my invention and desire to secure by Letters Patent is:—

- 10 1. The combination with an electric signaling circuit and a clock mechanism, of a disk or plate mounted to be turned by said clock mechanism and provided with flexible circumferential contact teeth arranged for definite intervals of time, and which when in the plane of the disk are adapted to close said electric signaling circuit; a signal included in said signaling circuit; and a so-called scissor-switch in circuit therewith and comprising two levers having outer contact arms and inner arms of different lengths, said levers being controlled by said clock mechanism and adapted to limit the duration of said signal produced when said circuit is closed.
- 15 2. The combination with an electric signaling circuit and a clock mechanism, of a disk or plate mounted to be turned by said clock mechanism and provided with flexible circumferential contact teeth arranged for definite intervals of time, and which when in the plane of the disk are adapted to close said electric signaling circuit; a signal included in said signaling circuit; a ratchet wheel operated by said clock mechanism; and a so-called scissor-switch in said circuit provided with arms of different length and engaging the teeth of said ratchet wheel said switch being adapted to limit the duration of said signal produced when the said circuit is 40 closed by said contact teeth.
- 20 3. An electric signaling clock comprising an ordinary clock mechanism; an electric signaling circuit containing a source of electricity and one or more suitable signaling devices; a disk mounted to turn with said clock mechanism and provided with flexible circumferential contact teeth arranged for definite intervals of time and which when in the plane of the disk are adapted to close said electric signaling circuit; and means in circuit with said disk adapted to limit the duration of the signal produced when the circuit is closed by said contact teeth.
- 25 4. An electric signaling clock comprising an ordinary clock mechanism; an electric signaling circuit containing a source of electricity and one or more suitable signaling devices; a disk mounted to turn with said clock mechanism and provided with flexible circumferential contact teeth arranged for definite intervals of time and which when in the plane of the disk are adapted to close said electric signaling circuit; and a scissor-switch in circuit with said disk adapted to limit the duration of the signal 45 produced when the circuit is closed by said contact teeth.
- 30 5. An electric signaling clock comprising an ordinary clock mechanism; an electric signaling circuit containing a source of electricity and one or more suitable signaling devices; a disk mounted to turn with said clock mechanism and provided with flexible circumferential contact teeth arranged for definite intervals of time and which when in the plane of the disk are adapted to close said electric signaling circuit; and means in circuit with said disk adapted to limit the duration of the signal 50 produced when the circuit is closed by said contact teeth.
- 35 6. An electric signaling clock: the combination with a plurality of individual clock-actuated circuit closing means; of means adapted to automatically change the circuit from one of said closing means to another.
- 40 7. In an electric signaling clock: the combination with a plurality of individual clock-actuated circuit closing means; of means adapted to automatically change the circuit from one of said closing means to another; and means to temporarily suspend the action of said circuit closing means.
- 45 8. In an electric signaling clock: the combination with a plurality of clock-actuated circuit closing means; of means adapted to change the circuit from one of said closing means to another; means to temporarily suspend the action of said closing means; and means to limit the duration of the signal produced when the signaling circuit is closed.
- 50 9. In an electric signaling clock: the combination with a plurality of clock-actuated circuit closing disks provided with flexible contact teeth, of clock actuated means adapted to change the circuit from one disk to another.
- 55 10. An electric signaling clock comprising an ordinary clock mechanism; an electric signaling circuit containing a source of electricity and one or more suitable signaling devices; a number of disks mounted to turn with said clock mechanism and provided with flexible circumferential contact teeth arranged for definite intervals of time and which when in the plane of their respective disks are adapted to close said electric signaling circuit; and means to change the circuit from one disk to another and to temporarily suspend the action of said teeth.
- 60 11. An electric signaling clock comprising an ordinary clock mechanism; an electric signaling circuit containing a source of electricity and one or more suitable signaling devices; a number of disks mounted to turn with said clock mechanism and provided with flexible circumferential contact teeth arranged for definite intervals of time and 65 produced when the circuit is closed by said contact teeth.

produced when the circuit is closed by said contact teeth.

5. An electric signaling clock comprising an ordinary clock mechanism; an electric signaling circuit adapted to be closed by contact teeth and containing a source of electricity and one or more suitable signaling devices; a disk mounted to turn with said clock mechanism and provided with flexible circumferential contact teeth arranged for definite intervals of time and which when in the plane of the disk are adapted to close said electric signaling circuit; means controlled by said clock mechanism to temporarily suspend the action of said teeth; and means in circuit with said disk to limit the duration of the signal produced when the circuit is closed by said contact teeth.

6. In an electric signaling clock: the combination with a plurality of individual clock-actuated circuit closing means; of means adapted to automatically change the circuit from one of said closing means to another.

7. In an electric signaling clock: the combination with a plurality of individual clock-actuated circuit closing means; of means adapted to automatically change the circuit from one of said closing means to another; and means to temporarily suspend the action of said circuit closing means.

8. In an electric signaling clock: the combination with a plurality of clock-actuated circuit closing means; of means adapted to change the circuit from one of said closing means to another; means to temporarily suspend the action of said closing means; and means to limit the duration of the signal produced when the signaling circuit is closed.

9. In an electric signaling clock: the combination with a plurality of clock-actuated circuit closing disks provided with flexible contact teeth, of clock actuated means adapted to change the circuit from one disk to another.

10. An electric signaling clock comprising an ordinary clock mechanism; an electric signaling circuit containing a source of electricity and one or more suitable signaling devices; a number of disks mounted to turn with said clock mechanism and provided with flexible circumferential contact teeth arranged for definite intervals of time and which when in the plane of their respective disks are adapted to close said electric signaling circuit; and means to change the circuit from one disk to another and to temporarily suspend the action of said teeth.

11. An electric signaling clock comprising an ordinary clock mechanism; an electric signaling circuit containing a source of electricity and one or more suitable signaling devices; a number of disks mounted to turn with said clock mechanism and provided with flexible circumferential contact teeth arranged for definite intervals of time and 130 produced when the circuit is closed by said contact teeth.

which when in the plane of their respective disks are adapted to close said electric signaling circuit; means to change the circuit from one disk to another and to temporarily suspend the action of said teeth; and means to limit the duration of the signal produced by the said contact teeth.

Signed at New York city in the county of New York and State of New York this third day of August, A. D. 1905.
